US00D969631S

(12) **United States Design Patent** (10) **Patent No.:** **US D969,631 S**
(45) **Date of Patent:** **** Nov. 15, 2022**

(54) **MOTION SENSOR**

(71) Applicants: **Neos Ventures Limited**, London (GB);
Tianjin Hualai Technology Co., Ltd,
Tianjin (CN)

(72) Inventors: **Xin Lingyun**, Tianjin (CN); **Anthony Lee Weston**, London (GB)

(**) Term: **15 Years**

(21) Appl. No.: **29/762,852**

(22) Filed: **Dec. 18, 2020**

(30) **Foreign Application Priority Data**

Jun. 19, 2020 (EM) 008012694-0003

(51) **LOC (13) Cl.** **10-04**

(52) **U.S. Cl.**

USPC **D10/70; D10/106.6**

(58) **Field of Classification Search**

USPC D10/70, 106.6

(57) **CLAIM**

The ornamental design for a motion sensor, as shown and described.

DESCRIPTION

FIG. 1 is a first perspective view of a motion sensor showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
